US00D992186S

(12) **United States Design Patent** (10) **Patent No.:** **US D992,186 S**
Sherman et al. (45) **Date of Patent:** **** Jul. 11, 2023**

(54) **LIGHTED CABLE TERMINATION ASSEMBLY**

(71) Applicant: **nVent Services GmbH**, Schaffhausen (CH)

(72) Inventors: **Adam Sherman**, Newark, CA (US); **Rajasree Andeth Nair**, Kerala (IN); **Subhash Thanathalil Kumaran**, Kerala (IN)

(73) Assignee: **nVent Services GmbH**, Schaffhausen (CH)

(**) Term: **15 Years**

(21) Appl. No.: **29/815,561**

(22) Filed: **Nov. 15, 2021**

Related U.S. Application Data

(60) Continuation of application No. 29/769,139, filed on Feb. 3, 2021, now Pat. No. Des. 936,261, which is a continuation of application No. 29/684,256, filed on Mar. 19, 2019, now Pat. No. Des. 938,636, which is a division of application No. 29/493,147, filed on Jun. 5, 2014, now Pat. No. Des. 843,625.

CLAIM

The ornamental design for a lighted cable termination assembly, as shown and described.

DESCRIPTION

FIG. 1 is an isometric view of a front, top, and left side of a lighted cable termination assembly; and,

FIG. 2 is a left side elevational view of the lighted cable termination assembly of FIG. 1.

The dash-dash-dash broken lines are included to show portions of the lighted cable termination assembly that form no part of the claimed design. The dash-dot-dash broken lines depict boundary lines and form no part of the claimed design.

1 Claim, 2 Drawing Sheets
